UNITED STATES PATENT OFFICE.

ROBERT BURNS BONE, OF NEW HAVEN, CONNECTICUT.

PAPER-PADDING APPARATUS.

1,285,914.

Specification of Letters Patent.

Patented Nov. 26, 1918.

Application filed May 25, 1917. Serial No. 170,907.

To all whom it may concern:

Be it known that I, ROBERT B. BONE, a citizen of the United States, and a resident of New Haven, in the county of New Haven and State of Connecticut, have invented a new and Improved Paper-Padding Apparatus, of which the following is a full, clear, and exact description.

This invention relates to paper padding apparatus or what are known ordinarily as paper padding racks, or racks for holding paper while being padded.

More definitely stated the invention pertains particularly to a vertical rack having parallel side bars with which coöperate in a self holding manner a plurality of flat plates which serve to prevent horizontal displacement or disarrangement of the paper or stacks of paper being operated upon, while at the same time permitting movement of the paper in vertical lines to allow for the compression that may be applied thereto.

Another object of the invention is to provide a vertical frame or rack which includes a vertical board against which the paper may be stacked in practice in perfect alinement along that edge or side to which the glue and fabric are applied in the operation of padding, said board being held removably in place so that after the stacking is completed the board may be removed, affording direct access to the edge or face of the paper to be padded.

A further object of the invention is to provide improved facilities for detachably holding said front board in place.

Another object of the invention is to provide a rack of the character indicated, with means for rotating it around a vertical axis whereby the loading of the rack and the subsequent padding of the paper loaded therein may be accomplished with the rack stationed close to the wall so that very little floor space is required.

Another object of the invention is to provide a padding attachment adapted for the accommodation of stacks of sheets of paper of different sizes at the same time, or in other words for the making of pads of different sizes simultaneously, the holding means or the devices for preventing the lateral or longitudinal displacement of the sheets being adapted to operate just the same whether the sheets are all of the same size or not.

With the foregoing and other objects in

view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation of my improved apparatus, the rack being filled with a stack of paper and having the front thereof turned toward the wall.

Fig. 2 is a view in elevation of the opposite side of the rack with the front turned away from the wall and the front board unfastened ready for removal.

Fig. 3 is a front elevation with the front board removed.

Fig. 4 is a plan view with the parts shown in the position in Fig. 1.

Fig. 5 is a detail perspective view indicating one of the corner pieces and the relation of the lower end of the front board thereto.

Fig. 6 is a plan view of the rack bottom indicating in dotted lines the position of the front board and also indicating sheets of paper of different sizes being manipulated.

Fig. 7 is a detail perspective view of one of the holding plates; and

Fig. 8 is a detail plan view of another form of holding plate and the coöperating vertical bar in horizontal section.

Referring now more particularly to the drawings I show a paper padding apparatus comprising a rack or frame having a bottom or base 10, vertical parallel side bars 11 and 12 and a top cross bar 13. The base is supported upon a turntable 14 having a central pivot 15 in a foot piece 16 secured or supported upon the floor of the building in any suitable manner. The axis of this pivot is vertical and lies within a vertical plane substantially central of the two side bars. The cross bar is formed with a hole for a pivot 17, the axis of which is in vertical alinement with the axis of the pivot 15 and is carried by a wall bracket 18 of any convenient type. The foot 16 and the bracket 18 are so located that the rack may swing freely around the vertical axis of the two pivots and will be held so that it is not liable to tilt in any direction from said axis.

As shown best in Fig. 1 the front edge

of the base 10 lies slightly ahead of the vertical plane of the two front edges of the side bars 11 and 12, but said base extends rearwardly to any desired distance beyond 5 the rear edges of the bars so as to firmly support large sheets of paper or stacks of paper to be padded. The cross bar 13, however, extends forwardly as indicated at 13' to a certain distance beyond the front 10 edges of the side bars.

At the lower front corners of the rack or frame are located a pair of corner pieces 19 and 20, the rear ends of which are secured to the side edges of the base or to 15 the lower ends of the bars 11 and 12. These corner pieces provide definite pockets or seats for the lower corners of a front board 21 having a perfectly flat or true inner surface, the upper end of which is adapted to bear securely against the front edge of the cross bar or portion 13' of the cross bar 13. This board is adapted to be locked temporarily in this perfectly vertical position by 20 means of any convenient hooks or hasps 22 carried by the side bars and adapted to co-operate with eyes 23 carried by the front board. When the rack is constructed and assembled as described herein and is turned with the front toward the wall, as shown in 25 Fig. 1, piles or stacks of paper to be padded are placed directly upon the base 10 and piled in this manner with two adjacent edges lying squarely against the smooth flat inner surface of the front board and the inner surface 30 of one of the side bars. Since these two vertical surfaces are at exactly right angles to each other the sheets of paper applied thereto in perfect order may be retained in such order by contact with said surfaces. If 35 desired a stack or pile of paper of a larger or smaller size, or even of the same size as the one first referred to, may be piled upon the base simultaneously with the first mentioned pile or stack. The inner surface of 40 the other side bar is brought into action in this connection along with the inner surface of the front board. (See Fig. 6).

The placing of the piles or stacks of paper upon the base and against the vertical front 45 board and side bars, or loading of the rack as it is called in practice, is accomplished from the rear of the rack while the front thereof is turned toward the wall. When a stack of suitable height is loaded upon the base means it is necessary to retain the same in stable position. For this purpose I provide a series of holding plates 24, as shown in detail in Fig. 7, each of which has end 50 notches or extensions having positive connection with the side bars 11 and 12. The plates 24 are shown as having notches 25 which receive the side bars therein while the extensions 26 lie on opposite sides of the bars. Without these locking plates 24, or 55 their equivalent, the stack of paper would

be liable to spring or bulge laterally with the result of a tumbling or spilling thereof if the stack were high enough to represent an economical transaction. In other words for the apparatus to be useful in the greatest 70 economy for space and the making of a high stack for the economical application of the glue and fabric thereto it is essential that a considerable number of these locking plates be employed to prevent the tilting, 75 bulging or other lateral displacement with respect to the flat front board.

After the stack of sheets to be padded has reached the desired height, or a plurality of stacks have been formed and locked from 80 lateral displacement as above indicated, the operator places a weight 27 upon the top-most plate 24 which will serve to put the entire stack or stacks under suitable compression and hold the same temporarily until the padding operation is completed. The operator then swings the rack around through an arc of a circle according to his convenience, as for example through 180° as shown in Fig. 2, bringing the front of the 85 apparatus remote from the wall. He then, while the weight is still in place holding the stack and locking plates steady, will remove the front board by first unhooking the hasps 22 and then lifting the board vertically out 90 of the corner pieces 19 and 20. From the construction of the lower part of the apparatus the edges of the paper to be treated with glue and fabric are all free or clear of the rack structure so that the glue may be 95 applied readily to the entire front face of the stack of paper, covering all portions of the edges of the paper to be reached, and yet without danger or necessity for smearing the glue upon any portion of the rack. In 100 this connection also it is to be noted that the plates 24 may be of such a width as to stop a trifle short of the plane of the front board so that the front edges of the locking plates need not be smeared with the glue. These 105 plates 24 may be made of any suitable material or thickness for their purpose but I suggest for this purpose the use of No. 25 gage sheet metal, the thickness therefore of which is not great enough to disturb the vertical 110 alignment of the front edges of the paper which may overlap the same. After the board is removed the glue is spread over the entire front face of the stack, and the strip of fabric is applied directly thereto and if 115 desired another coat of glue may be applied over the fabric, depending upon the particular requirements of any special job. After the glue has dried the padded paper 120 may be removed from the rack, first removing the weight 27 from the uppermost plate 24, the several tablets or sections of the padded paper being then separated in any convenient or well known manner.

In Fig. 8 I suggest a form of side bar 11' 125

having a vertical groove 11^a into which a lug or tongue 26' of a different form of locking plate 24' may project. The bar 11', however, may be of the same general dimensions 5 in cross section as the bars 11 and 12 above referred to so that the plates 24 may be employed in connection therewith, if desired, as well as the plates 24'.

As shown in Figs. 1 and 2 to the rear face 10 of the front board 21 and on opposite sides of the smooth flat portion thereof against which the paper is stacked, are secured a pair of studs 21' which are adapted to bear against the front edges of the side bars 11 15 and 12 to hold the bottom end of the front board snugly against the outer ends of the corner pieces. The length of these studs is exactly equal to the extension 13' or that part of the cross bar 13 which projects forwardly of the front edges of the side bars. 20

I claim:

1. In a paper padding apparatus, the combination of a frame comprising a base, a pair of vertical spaced parallel side bars extending upwardly from the base and a cross bar connecting the upper ends of the side bars, means to support the frame for free rotation around a vertical axis, said side bars each having straight parallel front and rear edges, means coöperating with the frame to receive a stack of paper with at least two of its faces in true vertical alignment at right angles to each other, and a series of flat plates each having end projections engaging slidably with the straight edges of the side bars to permit vertical 25 30 35

movement of the plates but prevent lateral movement thereof and of the stack of paper, substantially as set forth.

2. In a paper padding apparatus, the combination of a frame comprising a base, a pair of upright parallel side bars having vertical front edges, a pair of corner brackets extending forwardly from the base and the lower ends of the side bars and a cross 40 bar connecting the upper ends of the side bars and having an extension reaching forwardly of the upper ends of the said front edges, a removable front board having its lower end received in said corner brackets 45 and adapted to lie squarely against the front edge of said cross bar extension, and a pair of studs carried by the side edges of the front board and adapted to bear against the front edges of the side bars to hold the front 50 55 board vertical.

3. In a paper padding apparatus, the combination of a frame comprising a base, a pair of upright spaced parallel side bars extending upward from the base and a cross-bar 60 connecting the upper ends of the said bars, said side bars each having straight parallel edges, means coöperating with the frame to receive a stack of paper with at least two of its faces in planes at right angles to each 65 other, and a series of flat plates each having end projections engaging slidably with the straight edges of the side bars to permit free movement of the plates along the bars but preventing lateral movement thereof and of 70 the stack of paper, substantially as set forth.

ROBERT BURNS BONE.
